UNITED STATES PATENT OFFICE.

WILLIAM U. WATSON, OF CHICAGO, ILLINOIS.

PUMP.

1,166,098.

Specification of Letters Patent. Patented Dec. 28, 1915.

Application filed November 7, 1914. Serial No. 870,721.

To all whom it may concern:

Be it known that I, WILLIAM U. WATSON, a citizen of the United States, residing at Chicago, in the county of Cook and State of Illinois, have invented a certain new and useful Improvement in Pumps, of which the following is a specification.

My invention relates to pumps, more particularly air compressors, and for the purpose of illustration is shown embodied in a so-called "spark plug pump" used in connection with a multicylinder internal combustion engine for obtaining compressed air.

The general object of the invention is to obtain a simple and efficient device of this character.

One of the specific objects of the invention is to provide a simple and sure acting valve for supplying air to the attached engine cylinder in case there is, for any reason, a deficiency of air pressure therein. This valve in permitting comparatively free access of air to the engine cylinder causes the air to be drawn through the valve port instead of through the carburetor of the engine. This avoids or reduces the waste of gas.

Other objects will be apparent from the following description taken in connection with the accompanying drawings, in which—

Figure 1 is a longitudinal sectional view of the complete device attached to one of the cylinders of a multicylinder internal combustion engine. Fig. 2 is a plan section on the line 2—2, Fig. 1. Fig. 3 is a perspective of the inlet valve. Fig. 4 is a detail sectional view showing some of the valve mechanism on an increased scale.

Similar numerals refer to similar parts throughout the several views.

Screwing into the engine cylinder 1 is a nipple 2 having a longitudinal duct 3 leading from the inside of the engine cylinder to the inside of a cylinder 4 which for distinction I shall refer to as the motor cylinder. For convenience, the nipple 2 and cylinder 4 may be made of separate pieces screwed together, as shown, or may be integral with each other. The nipple has a number of inlet ports 5 for admitting air laterally into the duct 3. These are arranged symmetrically for balancing the pressure on the inlet valve. Said inlet valve, which is

shown in perspective in Fig. 3, slides vertically within the nipple and in the present form consists of a hollow cylinder 6. Its function is to open and close the inlet ports 5. Means are provided for limiting the travel of the valve, the means here shown being the annular shoulder 7 formed in the nipple for engaging the upper end of the valve and the annular shoulder 8 for engaging the flange 9 at the lower end of the valve. The downward movement of the valve is limited by the ring 10 screwing into the lower end of the nipple. The valve is so fitted as to slide very freely and to drop by gravity unless it is held up by some positive force.

The opening through the valve is constricted, there being an inwardly projecting annular flange 11. The opening 12 through said flange is of smaller diameter than the remainder of the passage through the valve and hence the uprush of air from the cylinder 1 tends to raise the valve and hold it in raised position.

A piston 15 fits within cylinder 4 and is connected by a cylinder 16 to a piston 17 working in the upper cylinder 18 which is of smaller diameter than cylinder 4. Cylinder 16 is closed at the bottom and is provided with a stationary plunger mounted at the lower end of the stem 20 which is hollow and has a delivery mouth 21 outside of the cylinder 18. The piston 17 has a vertical passage 22 guarded by a check valve 23 so arranged that air may pass upward through said piston but not in the reverse direction. Piston 17 also has ports 25 leading from cylinder 18 downward to cylinder 16. Air is prevented from traveling in the reverse direction through the ports 25 by a check washer 26 constructed of rubber or other suitable material. The plunger at the lower end of the stem 20 is provided with a check washer 30 held in position against the annular shoulder 31 of the stem by a retaining ring 32. The longitudinal duct 19 in the stem 20 is guarded by a check valve 35 held to its seat by a spring 36, the arrangement being such that air is permitted to flow up through duct 19 but is prevented from flowing in the reverse direction.

Air is prevented from passing from the lower end of cylinder 18 directly to cylinder 4 by a spring washer 40 held in position by

retaining plates 41. Said washer, however, permits the air to flow from cylinder 4 to the lower end of cylinder 18.

An inlet valve is located near the upper end of cylinder 4, said valve consisting of a casing 42 provided with a check ball 43 held to its seat by a spring 44.

In operation, when the air in the engine cylinder 1 is under compression the up-rush 10 of said air through the duct 3 raises the inlet valve 6 and closes the ports 5. Hence the air rushes up into cylinder 4 beneath the piston 15 therein and forces the air above said piston to flow up past the washer 40 15 into the lower end of cylinder 18. As the diameter of the cylinder 18 is smaller than that of cylinder 4, the air within the cylinder 18 is raised to a higher pressure than in the cylinder 4, and said air is forced down 20 through the ports 25, past the washer 26, into the upper end of the cylinder 16. After the compression stroke in the engine cylinder 1 is completed and the suction stroke commences, the vacuum or partial vacuum 25 in the cylinder 1 permits the valve 6 to drop and uncover the inlet ports 5. This downward movement is accelerated by the down-rush of air in the nipple 2. The size of the ports 5 is not great enough to supply all 30 of the air called for by the engine cylinder, and hence the partial vacuum in the duct 3 causes the piston 15 and parts attached thereto to descend. The descent is also aided by the back pressure in the pump and this 35 may be augmented by springs if desired. The descent of piston 15 causes the inlet valve 43 to open and admit air to the top of cylinder 4. The air in the bottom of cylinder 18 is forced up through piston 17 into 40 the top of said cylinder while the air in the top of cylinder 16 is simultaneously forced past the washer 30 into the bottom of said cylinder to be subsequently delivered up through the duct 19.

45. From the foregoing it will be seen that the inlet valve 6 is of very simple construction and of free operation and normally remains open. Furthermore whatever air is drawn in through the inlet ports 5 reduces 50 by the same quantity the air drawn through the carburetor of the engine. Hence there is decreased vaporization of the fuel oil of the engine and a commensurate saving in fuel results.

55. Having thus described my invention, what I claim as new and desire to secure by Letters Patent is:—

1. A compressor having a motor cylinder, a piston, a cylindrically chambered nipple 60 leading to said cylinder for supplying gas thereto, said nipple having a port at the side arranged radially and in a plane transverse to the length of the nipple, and a cylindrical valve sliding in said nipple to cover 65 and uncover said port, said valve having a

passage extending longitudinally through it and constricting somewhat the size of the passage in the nipple whereby a gas stream flowing longitudinally through the nipple moves said valve.

2. In combination, a motor cylinder, a cylindrical nipple constituting an inlet for said cylinder, said cylinder being open at the receiving end and said nipple having an inlet port in the side arranged radially in a 70 plane transverse to the length of the nipple, and a valve slidable longitudinally in said nipple to cover and uncover said port, said valve forming a hollow cylinder and being subject to the kinetic energy of the gas 75 stream flowing longitudinally through said nipple from the receiving end thereof.

3. In combination, a motor cylinder, a nipple leading thereto for supplying actuating fluid to the cylinder, said nipple having an approximately cylindrical bore, and an inlet port leading to the bore from the side, a cylindrical valve fitting said nipple and sliding therein to cover and uncover said port, said valve restricting the longitudinal 85 passage in the nipple whereby the stream of actuating fluid flowing longitudinally through said nipple toward the cylinder operates the valve to close the inlet port in the side of the nipple.

4. A fluid actuated air compressor having a cylinder and a driving piston therein, a cylindrical nipple constituting an inlet for said cylinder, said nipple being arranged vertically and having an inlet port in the 100 side arranged radially in a plane transverse to the length of the nipple, said nipple having an opening below said port for receiving actuating fluid, a hollow cylindrical valve sliding vertically in said nipple to cover and uncover said port, said valve when raised closing said port and when lowered opening said port, said valve tending to open under the action of gravity and restricting the longitudinal passage in the nipple whereby a 105 stream of actuating fluid flowing through the nipple toward the cylinder tends to raise said valve and cause it to close said port.

5. In a compressor, a plurality of cylinders one of which is of greater diameter than the other, a piston in each of said cylinders, means for connecting said pistons whereby the movement of the larger piston is imparted to the smaller piston, a cylindrically bored duct for connecting the larger 115 cylinder to one of the cylinders of a multi-cylinder internal combustion engine, a lateral radially arranged opening in said duct for admitting air thereinto, and a normally open cylindrical valve operated by the air or other gas in said duct for controlling said opening, said valve sliding in said duct to cover and uncover the lateral opening in said duct.

6. In a compressor the combination of a 120

- motor cylinder, a cylindrical nipple for conveying gas to the motor cylinder, a piston in the motor cylinder, a cylinder of smaller diameter than the motor cylinder, a piston 5 in said smaller cylinder, means connecting said pistons together, means for delivering compressed air from the smaller cylinder controlling said valve, a radially arranged port in said nipple for admitting atmospheric air thereinto, and a hollow cylindrical slide valve, said valve being located in said nipple and partially obstructing the passage therein, whereby said valve is subject to the dynamic force of a gas stream in 10 said nipple.
7. In a compressor the combination of a motor cylinder, a nipple for conveying gas to the motor cylinder, a piston in the motor cylinder, a cylinder of smaller diameter 20 than the motor cylinder, a piston in said smaller cylinder, means connecting said pistons together, means for delivering compressed air from the smaller cylinder, said nipple having a plurality of lateral openings 25 for admitting atmospheric air to the interior of said nipple, and a cylindrical valve sliding freely within said nipple to cover and uncover the lateral openings therein, said openings being arranged symmetrically around said valve whereby the 30
- pressure upon the valve is balanced, and said valve partially obstructing the flow of gas longitudinally through said nipple whereby the kinetic energy of the gas stream longitudinally in said nipple is 35 availed of for operating said valve.
8. In a compressor the combination of a motor cylinder, a cylindrical nipple for conveying gas to the motor cylinder, a piston in the motor cylinder, a cylinder of smaller 40 diameter than the motor cylinder, a piston in said smaller cylinder, means connecting said pistons together, means for delivering compressed air from the smaller cylinder, a radially arranged port in said nipple for 45 admitting atmospheric air thereinto, and a hollow cylindrical slide valve for controlling said port, said valve being located in said nipple and partially obstructing the passage therein, said valve sliding vertically, whereby it is subject to the action of gravity, said valve when lowered holding said port uncovered.

In witness whereof, I have hereunto subscribed my name in the presence of two 55 witnesses.

WILLIAM U. WATSON.
